W. C. PENTY.
SPRINKLER HEAD.
APPLICATION FILED JUNE 30, 1920.

1,385,392.

Patented July 26, 1921.

UNITED STATES PATENT OFFICE.

WILLARD CLARKE PENTY, OF COLUMBUS, OHIO.

SPRINKLER-HEAD.

1,385,392.

Specification of Letters Patent. Patented July 26, 1921.

Application filed June 30, 1920. Serial No. 392,942.

To all whom it may concern:

Be it known that I, WILLARD CLARKE PENTY, a citizen of the United States, and a resident of Columbus, in the county of 5 Franklin and State of Ohio, have invented certain new and useful Improvements in Sprinkler-Heads, of which the following is a specification.

My invention relates to sprinkler heads 10 employed in automatic sprinkling systems, and a purpose of my invention is the provision of a sprinkler head which is so constructed as to allow of the proper spreading and falling of the water on all parts of the 15 area allotted for fire protection by the particular valve. Furthermore, my invention allows a quicker and more efficient adjustment of the valve and prevents leakage of water from the head, the sprinkler head 20 being capable of quick assembly to facilitate installation.

I will describe one form of sprinkler head embodying my invention and will then point out the novel features thereof in the claim.

25 In the accompanying drawings:

Figure 1 is a perspective view showing one form of sprinkler head embodying my invention in locked position.

Fig. 2 is a central vertical sectional view 30 of the sprinkler head shown in Fig. 1.

Fig. 3 is a view showing in section one of the water supply pipes of a sprinkling system having applied thereto the sprinkler head shown in the preceding views, the latter 35 being in released position.

Similar reference characters refer to similar parts in each of the several views.

Referring specifically to the drawings, A designates a short section of pipe or sleeve 40 formed adjacent its upper end with an annular head B. Below the head B the outer surface of the sleeve A is screw threaded to permit of its application to the water supply pipe of a sprinkling system, as shown in Fig. 45. 3. The sleeve A within the head B is formed to provide a valve seat C upon which reposes a rubber gasket D. Adapted to seat upon the gasket D is a valve E which is of a diameter corresponding to that of the seat 50 C so as to completely close the upper end of the sleeve A.

The head B carries a substantially U-shaped yoke designated generally at F and which comprises a stationary section 15 and 55 a movable section 16. The stationary section 15 is formed integral with the head B

and constitutes a major portion of the yoke, as will be understood from a consideration of Fig. 3. The section 15 carries adjacent its free end a deflecting cap G which, as 60 shown, is of concaved formation and formed with a fluted edge. The cap G is detachably associated with the section 15 by means of a screw H which, as shown in Fig. 2, is threadedly fitted within suitable projections formed 65 on the inner side of the sections. The movable section 16 is hingedly supported upon the cap G by means of a pin K which extends through a suitable recess formed in the periphery of the pin and through a projection 16^a formed on the end of the section 16. The section 16 carries intermediate its 70 ends a laterally extending arm 16^b which, in the locked position of the yoke, is adapted to overlie the valve in the manner shown in 75 Figs. 1 and 2. Threadedly fitted within the arm 16^b is a set screw L, the lower end of which normally engages the valve E and is disposed within a suitable recess formed in such valve thereby effecting a locking of the 80 valve against displacement from the seat C.

The confronting ends of the sections 15 and 16 are preferably formed with an interfitting connection which as illustrated to advantage in Fig. 1 comprises a tongue 15^a 85 formed on the end of the section 15, and a groove 16^c formed on the end of the section 16 and of a contour to receive the tongue.

Because of the manner in which the section 16 is pivotally supported upon the head 90 B, it will be clear that such section normally tends to gravitate to the position shown in Fig. 3. However, the section 16 is normally locked in the position shown in Fig. 1 by means of a bar M which is supported upon 95 studs S in a manner to rigidly connect the two sections and retain the same in yoke formation. The bar M is formed of any fusible substance such as lead or the like and is removably fitted upon the studs S so 100 as to permit the ready substitution of a new bar when the first bar is disrupted.

In the applied position of the sprinkler head to one of the nozzles of a sprinkling system, the parts of the head normally occupy the positions shown in Figs. 1 and 2. The pressure of water bearing against the valve E is ineffective to remove the valve from its seat by virtue of the set screw L, it being understood that the adjustment of 110 the screw is such as to securely hold the valve upon its seat, thus preventing the

slightest leakage of water from the sleeve A. However, because of the bar M, such section is held in yoke formation, thus maintaining the set screw in locking position with respect to the valve. When the bar M is disrupted, as a result of fire in the vicinity of the sprinkler head, the section 16 is consequently released and under the pressure of water acting on the valve E, is thrown to the position shown in Fig. 3. As the section 16 remains in this released position, the valve E is projected from its seat, thus allowing the water to be discharged through the sleeve A and into contact with the cap G. Because of the curvature of the cap, it will be clear that the water is deflected downwardly in all directions, so as to spray all parts of the allotted area, and to thereby effectively extinguish any and all fire within such area.

Although I have herein shown and described only one form of sprinkler head embodying my invention, it is to be understood that various changes and modifications may

be made herein without departing from the 25 spirit of the invention and the spirit and scope of the appended claim.

What I claim is:

A sprinkler head comprising, a threaded sleeve having a valve seat formed at one 30 end thereof, a head formed on said sleeve, a yoke carried by said head and comprising a stationary section fixed to the head and a movable section hingedly supported on said head for an outward swinging movement 35 from the stationary section, said sections having interfitting ends, a deflecting cap carried by the stationary section and overlying said valve seat, a valve normally reposing on said seat, an arm formed on the 40 movable section, a set screw adjustably mounted on said arm and engageable with said valve for retaining the same on said seat, studs formed on said sections, and a fusible bar removably fitted on said studs 45 and spanning said sections for the purpose described.

WILLARD CLARKE PENTY.
